W. I. STIMPSON

YARN CLEANER FOR SPOOLERS

Filed Aug. 30, 1927

UNITED STATES PATENT OFFICE.

WALLACE I. STIMPSON, OF HOPEDALE, MASSACHUSETTS, ASSIGNOR TO DRAPER CORPORATION, OF HOPEDALE, MASSACHUSETTS, A CORPORATION OF MAINE.

YARN CLEANER FOR SPOOLERS.

Application filed August 30, 1927. Serial No. 216,405.

This invention relates to a yarn cleaner and guiding device for spoolers and similar machines. Such a device is employed for cleaning or removing from the yarn or thread slubs and beads or bunches of fibre and for properly guiding the yarn in its passage through the cleaner to the yarn receiver upon which it is wound. This invention has to do with that type of device in which the yarn passes over a guide rod and in which a comb member provided with suitable comb teeth is pivotally mounted so that it may be swung into and out of cooperative relation with this guide rod.

15 One object of the invention is to provide a construction, for determining the position of the comb member when in cooperative relation with the guide rod, which may be readily adjusted but which is so located as 20 not to be accidentally or unintentionally adjusted. In the preferred form this construction is substantially concealed and can only be adjusted by a special tool provided for that purpose.

25 The type of yarn cleaner with which this invention is concerned usually comprises a bracket clamped to the traverse rod of the spooler or other machine and a further object of the present invention is to provide a 30 projection rigid with the bracket and extending above the comb member which will afford a natural point to receive a blow so that an operative attempting to adjust the device on the traverse rod by a hammer or 35 similar tool will not injure the device or disturb the adjustment between the comb member and guide rod and so also as to protect the device against any spool or other heavy object being dropped thereupon.

40 The nature and objects of the invention will appear more fully from the accompanying description and drawings and will be particularly pointed out in the claims.

In the drawings:

45 Fig. 1 is a front elevation of a yarn cleaner and guide embodying a preferred form of the invention.

Fig. 2 is a rear elevation of the construction shown in Fig. 1.

50 Fig. 3 is a view in vertical cross section taken on the line 3—3 of Fig. 2 with an adjusting tool shown in dotted lines and showing a traverse rod in cross section.

The device of this invention is shown as 55 adapted to be carried by a traverse rod 1

of a spooler, spinning or similar machine in which the traverse rod commonly has a vertical reciprocating movement to lay the yarn throughout the length of the yarn receiver as it is being wound thereon.

In such a device it is necessary to provide 60 means for cleaning or removing from the yarn any slubs, beads or bunches of fibre which occur and which would injure the quality of the yarn if carried on to the receiver. It is also desirable to provide suitable guides for directing the passage of the 65 yarn to the cleaner. It is also necessary to provide means for accurately adjusting the position of the comb member of the cleaner 70 with respect to these guides to insure the proper cleaning action.

In the device illustrated, a two-part 75 bracket is provided comprising the main section 2 and the clamping section 3 and these sections are clamped together by a suitable clamping bolt 4 so as to hold the bracket firmly upon the traverse rod 1.

The bracket has projecting laterally therefrom a main guide rod 5 and parallel with 80 it an auxiliary guide rod 6 over which rods the yarn passes on its way through the cleaner.

A comb member is pivotally mounted on 85 the bracket and provided with a set of comb teeth cooperating with the guide rod 5. In the construction illustrated, this comb member comprises, first, a flat blade 7 extending generally parallel with the guide rod and having a rearwardly projecting ear 8 and, 90 second, a comb proper shown as a flat plate 9 provided at its lower edge with a row of comb teeth 10. The comb plate 9 is adjustably secured to the blade 7 by bolts 11 and 12, the comb plate pivoting for that purpose on the bolt 12 and being provided with an aperture larger than the bolt 11. The entire comb member is pivotally mounted 95 in the bracket by means of a stud 13 extending through the bifurcated upper portion of the bracket and the ear 8 of the comb member. This enables the comb member when in its normal downward position, as shown in the drawings, to stand with the teeth in the required cooperative relation 100 with the guide rod 5, that is, parallel with this rod and accurately spaced from this rod. When it is desired to remove the slubs and fibres on the comb teeth or to renew the comb, the comb member is swung 110

upwardly on its pivot, thus giving ready access to the comb teeth.

It will be recognized that it is very important that the cooperative relation between the comb and the guide rod shall be accurately determined under all conditions and therefore it is necessary to provide means for adjustably determining with accuracy the distance between the row of comb teeth and the guide rod. It is important also that any adjustment provided for this purpose shall not be altered accidentally or unintentionally or by unauthorized persons.

In this invention a threaded recess 14 is formed in the bracket and opens at the front face of the bracket or that face which is adjacent the comb member. A headless set screw 15 is threaded into this recess and is provided with a conical point and thus forms an adjustable abutment against which the comb member rests when in its lowermost position. This abutment, therefore, accurately determines the cooperative position of the comb member with respect to the yarn guide.

It will be seen that this set screw is substantially concealed and in a position where it cannot be accidentally turned, where it cannot be struck or hit accidentally and where an unauthorized person would be unlikely to tamper with it.

This set screw is adjusted preferably by a special tool, shown in dotted lines in Fig. 3, which may be passed through a small opening 16 entering the recess 14 axially thereof from the rear of the bracket. This opening is smaller than the recess and the set screw is still substantially concealed from view. The set screw is shown as provided at its rear end with a polygonal recess 17 to receive the polygonal end of a well known type of tool such as illustrated in dotted lines in Fig. 3.

As already noted, a yarn cleaner device of this type which is clamped on a traverse rod may be accidentally altered in its position on the traverse rod by being struck by a spool or other object falling from above or an operative may seek to adjust it on the traverse rod by pounding with a hammer or other object.

The bracket of this invention which is mounted on the traverse rod also presents a portion which extends vertically from its seat on the traverse rod and terminates in an integral rigid projection 18 above the comb member. The top of this projection thus affords a natural point for receiving a blow

from above and the force of this blow is transmitted directly in a right line through this portion of the bracket to the traverse rod. Thus if the operator strikes the bracket to adjust it on the traverse rod with a hammer or weight, there is no danger of disturbing the adjustment or position of the comb member with respect to the bracket. This portion of the bracket with this projection thus protects the comb member and other parts of the device from injury and from mal-adjustment.

The invention as a whole, therefore, presents a form of yarn cleaner and guide in which both the construction and the adjustment of the device are well protected.

Having thus described the invention, what is claimed as new, and desired to be secured by Letters Patent, is:

1. A yarn cleaner and guide for spoolers and similar machines comprising a bracket, a guide rod on the bracket over which the yarn passes, a comb member pivotally mounted on the bracket to swing into and out of cooperative relation with the guide rod, a threaded recess in the bracket opening at the face of the bracket adjacent the comb member, an opening in the bracket of smaller diameter than the recess and entering the recess axially thereof from the rear of the bracket and a set screw threaded into said recess and projecting therefrom at the face of the bracket to form an adjustable abutment for the comb member when in cooperative relation with the guide rod, the opening in axial alignment with the recess acting substantially to conceal the set screw while permitting it to be adjusted by a special tool inserted through said opening.

2. A yarn cleaner and guide for spoolers and similar machines comprising a bracket adapted to be mounted on a traverse rod, a comb member mounted on the bracket, a portion of the bracket extending vertically upward from its seat on the traverse rod and terminating in an integral rigid projection well above the comb member to afford a natural point for receiving a blow from above and transmitting the force of the blow directly in a right line through said portion to the traverse rod without disturbing the adjustment or position of the comb member with respect to the bracket and so protecting the comb member and other parts of the device from pounding or blows.

In testimony whereof, I have signed my name to this specification.

WALLACE I. STIMPSON.
